CLAIM

The ornamental design for the locking tabs for a snap-in spike, as shown and described.

DESCRIPTION

FIG. 1 is a perspective view of the locking tabs for a snap-in spike showing the new design;

FIG. 2 is a top view thereof;

FIG. 3 is a right side view thereof;

FIG. 4 is a left side view thereof;

FIG. 5 is a bottom view thereof;

The broken line showing of the environment in FIGS. 1-5 is for illustrative purposes only and forms no part of the claimed design.
